KEYBOARD CLEARING MECHANISM

Harold T. Avery, Oakland, Calif., assignor to
 Marchant Calculating Machine Company, a
 corporation of California

Application June 12, 1945, Serial No. 599,037

2 Claims. (Cl. 235—79)

1

The present invention relates to calculating machines of the type capable of performing problems in addition, subtraction, multiplication and division and more particularly to machines having what is known as a full or multiple column keyboard, a keyboard clearing mechanism and an "add key," the latter being effective, upon depression thereof, to enable the clearing mechanism to automatically release the depressed numeral keys during each cycle of operation of the machine. The add key may also be effective to limit the machine to one cycle of operation for each depression of the plus or minus bar regardless of the length of time during which the bar may be held depressed.

In machines of this character the add key may be held mechanically in depressed position throughout a series of additions or subtractions so that after the entry of each addend or subtrahend into the accumulator register the keyboard is automatically cleared, and the operator need only to set up and initiate entry of one item after another. However, in performing problems of division on this type of machine the procedure comprises the repeated subtraction of the divisor set up on the keyboard from the dividend or remainder, respectively, which stands in the accumulator register, and in performing divisions it is therefore necessary that the keyboard shall not be cleared during each subtractive operation for which reason the add key has to be released. For this purpose machines of the type referred to, and which have a special division lever or key for initiating automatic or semi-automatic division operation, may be provided with mechanism such as that shown in my Patent 2,256,799 whereby movement of the division lever or key into the division initiating position operates levers linked thereto which are effective to release the add key, thus making it unnecessary for the operator to manually release said key when changing from calculations of addition or subtraction to a division operation.

In certain instances, however, it may not be desirable to link additional mechanism adapted to effect release of the add key to the division key or lever of a calculating machine lest the operational load of the division key or lever become too high due to the added leverage required to release the add key. Then it may also be desirable to have automatic add-key-release upon initiation of calculations of division in machines that do not have a special division key or division mechanism and wherein a division-key-operated

2

release mechanism of the type shown in my above mentioned patent is therefore not feasible.

It is an object of the present invention to provide improved means for automatically releasing the add key in calculating machines when initiating calculations of division.

More specifically it is an object of the present invention to provide means in calculating machines by which the add key is automatically released when changing from calculations of addition or subtraction to calculations of division without burdening a division key, that may or may not be provided in the machine, with any special add-key-release linkage.

15 The present invention is based on the observation that in performing calculations of division the dividend is first entered into the accumulator register which causes the counter register to indicate the value of "1," which value must be cleared out before the division calculation is begun in order that a true quotient may appear in the counter register; it is also based on the fact that in divisions the first operation of the actuator driving mechanism immediately following

20 such clearance of the counter register is always a subtractive one. According to the present invention, therefore, sequential operation of the counter clearance mechanism and of the actuator driving mechanism in a subtractive direction is

25 arranged to bring about release of the add key.

It is a particular object of the present invention to provide normally ineffective release-mechanism for the add-key adapted to be placed into effective condition by operation of the counter register clearance mechanism and, thus conditioned, to become effective to release the add key only by an immediately subsequent operation of the actuator driving mechanism in a subtractive direction with no additive operation intervening.

30 It is an additional object of the present invention to provide a normally ineffective add-key release-mechanism of the type referred to which when placed into effective condition is adapted to 35 be restored to its normal condition during operation of the actuator driving mechanism.

It is still another object of the present invention to provide a normally ineffective add-key release-mechanism of the type referred to which, 40 when placed into effective condition, is adapted to be restored to its ineffective condition without effecting release of the add key, by immediately subsequent operation of the actuator driving mechanism in additive direction.

55 Other objects will appear from the following

description of a preferred form of the invention, reference being had to the accompanying drawings in which:

Figure 1 is a longitudinal section as viewed from the right of the machine, illustrating the add-key releasing-mechanism and part of the drive mechanism.

Figure 2 is a detail view in section showing the counter-clearance drive-mechanism and the control therefor.

Figure 3 is a fragmentary longitudinal section as viewed from the right illustrating the mechanism for conditioning the add-key release-mechanism.

Figure 4 is a detail view looking at the rear of the machine and partly in cross-section showing the driving and reversing mechanism.

Figure 5 is a fragmentary detail view of part of the mechanism shown in Figure 4.

Figure 6 is a section, as viewed from the left of the machine, showing the drive and drive control mechanisms.

Figure 7 is a section as viewed from the right showing the plus and minus bars and the mechanism controlled thereby for reversing the drive to the actuator.

Figure 8 is a diagrammatic view of the gear trains for the clearing mechanisms of the accumulator register and the counter register.

Figure 9 is a diagrammatic view of the gear trains for driving the accumulator and counter actuators.

The invention has been illustrated as adapted to calculating machines of the reversible rotary actuator type disclosed in the patents referred to hereinafter to which reference is hereby made for a full disclosure of details not particularly illustrated or described herein. It is to be understood, however, that the invention is not limited to the particular type of machine disclosed in the said patents in which the direction of operation of the actuators is controlled by a plus or minus bar or by a division initiating key, but it may also be embodied in a machine in which the direction of operation of the actuators is determined by the direction of rotation of a hand crank.

Keyboard

Calculating machines of the type illustrated such as that shown in the Friden Reissue Patent Number 18,911 include a numeral keyboard comprising a plurality of ordinal rows of keys each row including keys numbered 1 to 9 by depression of which factors are entered into the machine.

Key latching means is provided for each row of keys and is effective upon depression of a key to latch that key in depressed position until such a time as the key may be released by the disabling of said latching means.

In Figure 1 there is illustrated a single row of such keys. Each key 5 comprises a key stem 10 which is suitably mounted in the frame of the machine and is normally maintained in raised position by a spring 11. Mounted on the lower end of each key stem 10 is a projection or lug 12 which upon depression of a key latches under a locking slide 13 through which the key stems 10 pass. The locking slide 13 is slidably mounted on a key frame 14 of the machine in such a manner as to permit limited longitudinal movement thereof, and is normally maintained in its leftmost or forward position by a compression spring 16, compressed between the key frame 14 and an upturned end 17 of the slide. Upon de-

pression of any one of the numeral keys 5 the lug 12 moves the slide 13 rearwardly against the pressure of the spring 16, and after the lug passes beneath the slide 13, the slide is moved to its normal forward position by spring 16, thereby securely locking the key in depressed position.

The calculating machine in connection with which the present invention is illustrated, comprises a reversible rotary actuator 18 (Figures 3 and 4) which, upon depression of the numeral keys 5, receives the setting which corresponds to the value indicated upon said keys, the way in which the keys effect the setting of the actuator being disclosed in the Friden Patent Number 1,524,924. Rotation of the actuator transfers this value to the numeral wheels 19 of the accumulator register 20. When the actuator 18 is rotated in one direction the value introduced therein is added to the value standing in the accumulator register and when the actuator is rotated in the opposite direction the value introduced therein is subtracted from the value standing in said accumulator register.

The machine is also provided with a counter register comprising numeral wheels 23 (Figure 1), and a counter actuator comprising a one tooth gear or counter finger 118 which is keyed to, and slidable longitudinally on a shaft 119 by means of a flanged collar 120. The shaft 119 is driven in time with the accumulator, and the collar 120 and finger 118 are slid on the shaft by a forked member 114 which is coupled to the carriage of the accumulator 20 in a manner shown in the Friden Patent Number 2,028,540, so that as the carriage is shifted ordinarily, the counter finger 118 is also shifted in unison therewith but in opposite direction to enable it to actuate the proper denominational orders of the counter register.

Motor drive mechanism

Motor drive means is provided for driving the accumulator actuator 18 and the actuating finger 118. It includes appropriate gearing which is adapted to be reversibly connected to the actuators to drive the same in either of two directions.

Referring to the drawings, the driving means for the accumulator and counter actuators includes an electric motor 26 (Figures 8 and 9) having a pinion 39 mounted on the shaft 26a thereof which meshes with a gear 31. Gear 31 rotates a gear 32 which meshes with a gear 33 fixed on a drive shaft 34. A clutch 36 is included in the drive train, the driving member of which is a ratchet 37 (Figure 6) fixed to and driven by drive shaft 34, so that whenever the motor is energized the ratchet 37 rotates constantly in a counter-clockwise direction as viewed in Figure 6. Enclosing the ratchet 37 is a cylindrical housing 38 which constitutes the driven member of the clutch. A clutch driving pawl 41 is pivoted on a stud 40 carried by the housing 38, and is urged into driving engagement with the ratchet 37 by means of a small compression spring 42, which is disposed within a spring socket provided in the pawl 41 and is compressed between the pawl 41 and housing 38. When the clutch 36 is disengaged the pawl 41 is held out of driving relationship with the ratchet 37 by means of a clutch control mechanism comprising control dog 43 journaled on a stub shaft 44, supported in the machine frame. The left or backward arm of the clutch dog has integral therewith a nose 47, adapted to project through an appropriately posi-

tioned aperture in the clutch housing 38 when the clutch is in full cycle position, so as to engage the tail of the pawl 41 and thus hold the pawl 41 in clutch-disengaging position. The clutch dog 43 is urged to the clutch disengaging position shown in Figure 6 by a spring 48 tensioned between a right or forward arm of clutch dog 43 and a stud 46 on the base of the machine. Rocking of the clutch dog in a counter-clockwise direction to clutch engaging position, upon depression of either of a pair of control keys described later, removes the nose 47 from the clutch housing and permits the spring 42 to rock the pawl 41 into engagement with the ratchet 37, thereby effecting a driving connection between the driving and driven parts of the clutch.

Plus and minus bars

Means are provided to rock the clutch dog 43 to clutch engaging position for the desired number of revolutions to perform a selected calculation. A laterally projecting pin 51 (Figure 6), mounted on the forward arm of the clutch dog 43, normally lies within a notch 52 formed in the rear end of a control link 53. The forward end of the control link is pivoted at 54 to the forward arm of a bell crank 57, pivoted at 53 to a vertical support plate 59 forming part of the frame of the machine.

A plus bar 63 and a minus bar 72 (Figures 6 and 7) are so arranged that depression of either causes engagement of the clutch 36 described above. The plus bar 63 is carried by a two-armed frame 64 pivotally connected at opposite ends to the ends of two parallel bell levers 66 and 67, each pivoted to the machine frame by studs 68 and 69, respectively, which are disposed below and to the left of the respective connections of the levers and the plus bar frame 64 as viewed in Figure 7. A spring 70 is tensioned between the lower arm of bell lever 66 and a stud 70a mounted in the machine frame to the right of said arm, so as to maintain the plus bar in raised position. A roller 71 (Figures 7 and 6) is rotatably mounted on plus bar frame 64 and lies against the forward edge of bell crank 57 (Figure 6). Due to the position of studs 68 and 69 (Figure 7) with respect to the pivotal connections of levers 66 and 67 with the plus bar frame 64, depression of the plus bar will move frame 64 and roller 71 downwardly and toward the rear of the machine causing roller 71 to rock bell crank 57 counter-clockwise about its pivot 58 as viewed in Figure 6. This moves link 53 rearwardly which, in turn, rocks clutch dog 43 counter-clockwise into the clutch engaging position as described before.

Also the minus bar 72 is adapted to rock the bell crank 57 and cause engagement of the main clutch. For this purpose the arm 62 of bell crank 57 extends obliquely, upwardly and rearwardly and underlies a roller 76 pivoted to the stem of the minus bar 72 so that depression of the latter rocks the arm 62 of bell crank 57 counter-clockwise to cause a rearward shift of control link 53 and hence engagement of clutch 36. A torsion spring 73 is arranged to raise the minus bar 72 to its initial position when the operator releases the bar. When any depressed bar has returned to its initial position spring 48 returns clutch dog 43 to the clutch disengaging position shown in Figure 6 and it also returns link 53 and bell crank 57 to their initial positions in cooperation with the spring 61.

Reverse mechanism for accumulator actuator

As described hereinbefore the actuators are driven in one direction during additive or plus calculations and in the opposite direction during subtractive or minus calculations. The main clutch which is provided for driving the actuators is a one-direction clutch, therefore a reverse unit is provided in the drive train between the main clutch and the actuators. The reverse unit is under control of the plus and minus bars such that depression of the plus bar adjusts the reverse unit to its plus setting, if it is not already there, before it causes engagement of the main clutch, whereas depression of the minus bar adjusts the reverse unit to its minus setting.

This reversing mechanism is disclosed in the Friden Patent 1,682,901 to which reference is directed for details not specifically described herein.

Two gears 97 and 98 (Figures 4, 7, and 9) are so arranged that one or the other is operatively connected to clutch 36. The mechanism for connecting either gear 97 or gear 98 with the main clutch 36 is shown in section in Figure 4. It includes an axially shiftable shaft 101 which is centrally disposed within a tubular extension of the hub of clutch housing 38 on which are freely mounted gears 97 and 98. Shaft 101 carries a cross pin 99 which extends through a longitudinal slot in the tubular hub of the clutch housing 38 and depending upon the axial position of shaft 101 it also protrudes into a recess in the hub of either gear 97 or gear 98, thus coupling one or the other of the two gears to clutch housing 38. When the pin 99 is in the right end of the slot (as viewed in Figure 4), in the tubular extension of the hub of the clutch housing 38 it couples the latter to the gear 98, whereas when the pin is slid toward the left it disconnects the clutch from gear 98 and couples it to gear 97. When gear 97 is connected to the main clutch 36 the drive is transmitted through a train including gears 97, 102 and 103, shaft 104, gears 106, 107 and 108, to the accumulator actuator 18 in the direction of the arrows (Figure 9), whereas when gear 98 is connected to the main clutch, the drive is transmitted through a train including gears 98 and 103, shaft 104, gears 106, 107 and 108 to drive the accumulator actuator 18 in the opposite direction.

The plus and minus bars are arranged to effect the shifting of cross pin 99 in the following manner: Parallel to and slidable with shaft 101 is a second shaft 88 rigidly connected to shaft 101 by link 89 in such a manner that the two shafts slide together as a unit (Figures 3, 4 and 7). Near its right hand end shaft 88 is provided with a vertical slot which is engaged by a bent camming arm 87a of a reversing lever 87 (Figure 7). Reversing lever 87 is connected to a bell crank 84 through a link 82 all of which are normally held in the positions illustrated in Figure 7 by means of a spring 91. In this position camming arm 87a is kept in its clockwise position holding shaft 88 and 101 and cross pin 99 in their left positions (when viewing the machine from the front) and conducting the drive of the motor through gears 98 and 103 which operates the actuator 18 in a plus or additive direction.

When the minus bar 72 is depressed, however, a pin 77 (Figure 7), which is integral with the bar, engages a substantially horizontal arm 78 of the bell crank 84 and rocks the same counter-clock-

wise about its pivot 79. This pushes the link 82 backward, or toward the right as viewed in Figure 7, and rocks the reversing lever 87 counter-clockwise which slides the shaft 88 and 101 and cross pin 89 toward the right of the machine (or toward the left when viewing the machine from the rear as shown in Figure 4), conducting the drive through gears 97 and 102 which operates the actuator 18 in its minus or subtractive direction.

Upon release of the minus bar, the spring 91 (Figure 7) returns the reverse control mechanism to the plus position shown, but if the plus key is depressed before the spring has time to act, means are provided to supplement the action of spring 91 and insure the plus setting of the reverse unit before the clutch is again engaged. For this purpose a lever 92 is freely pivoted to the frame of the machine at 93, one end underlying the roller 71 of the plus bar 63 and the other end underlying the arm 78 of the bell crank 84, so that depression of the plus bar rocks the lever 82 counter-clockwise and forces the bell crank 84 to the plus position shown.

Counter driving and reversing mechanism

As mentioned briefly hereinbefore, the counter actuator is driven in timed relation with the accumulator actuator, so that the rotations or cycles of operation of the accumulator actuator are registered in the counter. In problems of division, the direction of rotation of the counter actuator must be reversed with respect to that of the accumulator actuator so that the number of times the divisor is subtracted from the dividend is registered additively in the counter.

This driving and reversing mechanism for the counter actuator comprises a gear 112 (Figure 9) which is splined to the shaft 111 of the counter tens-carry drum in such a way that it is slidable lengthwise on the shaft and into mesh with either gear 103 or a reverse idler gear 102 (Figures 9 and 1) so that the counter and accumulator actuators are driven in the same directions when gear 112 meshes with gear 102, and are driven in opposite directions when gear 112 meshes with gear 103. Counter finger 118 and its shaft 119 are driven from, and in the same direction as the counter tens-carry drum through a suitable gear train 118a, 118b and 118c. Suitable means such as a shifting fork or cam lever (not shown) may be provided for shifting the gear 112. The details of construction of the counter register and the counter reverse control mechanism are fully disclosed in the aforementioned Friden Reissue Patent Number 18,911.

Counter clearing mechanism

The operation of the clearing mechanism for the counter register will be briefly set forth in the following description, only those parts of the mechanism operatively associated with the present invention being illustrated in the drawings. For a full disclosure of the details of construction of this mechanism, reference is directed to the Friden Patent Number 1,858,397 and the Lerch Patent Number 1,935,851.

A zero resetting shaft 116 (Figure 1) extends axially through the numeral wheels 23. Rotation of this shaft through a complete revolution in a clockwise direction serves to return all of the numeral wheels to zero. It is immaterial for the purpose of the present invention, whether the zero resetting shaft 116 is rotated by hand by providing the shaft with a crank or similar device, or

by power, but in the machine with the aid of which the present invention is here explained, power operated means are provided for clearing the counter register.

5 The means for resetting the counter register to zero by power derived from the motor comprises a clear clutch drive shaft 121 (Figures 2 and 3) which is driven by the motor through a gear train including gears 39, 31, 32, 33, shaft 134, gears 122 and 123, and a gear 124 mounted on shaft 121. Associated with the drive shaft 121 is a clear clutch 126, substantially identical with the main clutch 36 shown and described in connection with Figure 6. The driven side of clutch 126 is connected to the zero resetting shaft 116 (Figures 2 and 3) through a gear train including gears 127, 128 and 129. The gear ratio of the train between the clutch and the shaft 116 is such that for each revolution of the clutch, the shaft 116 is likewise rotated one revolution.

20 A clear clutch control dog 130 is pivotally mounted on a shaft 135 (Figure 2) and the left or forward arm thereof is provided with a laterally extending pin 140 which is engaged by the forked end of a lever 145. This lever is pivoted on a stationary shaft 155 and is normally maintained in the position shown in Figure 2 by a spring 160. A key 150 is mounted on the end of the lever 145. Depression of key 150 rocks lever 145 counter-clockwise which in turn rocks clutch control dog 130 clockwise to cause engagement of the clear clutch with consequent clearance of the counter register.

Keyboard clearing mechanism

25 In order to set up a new problem on the keyboard of the machine immediately after a calculation in addition or subtraction, it is necessary to release the previously depressed keys. Although this may be performed by manually operated mechanism provided for this purpose, it is usually done by automatic keyboard clearing mechanism which may be selectively enabled or disabled by an "add key." When this key is in its raised position, it disables the clearing mechanism, but when latched down in its depressed position it enables the same to automatically release the numeral keys in response to the cyclic operation of the machine.

30 The machine embodying the present invention includes an add key 250 (Figure 1), the stem 131 of which is pivoted at 132 to one end of a lever 133. The lever 133 is pivoted intermediate its ends at 134 to the frame of the machine and both the add key 250 and the forward end of the lever 133 are normally held in elevated position by a spring 136 tensioned between the lower end of the key stem 131 and a stud 137 disposed at a higher level in the machine frame. The upper end of 35 the key stem 131 projects through a slot in the keyboard cover plate, and has a notch 255 which is adapted to engage the cover plate when the key is depressed to retain the key in depressed position. For this purpose the pressure of spring 136 is diagonally upward towards the rear of the machine which tends to urge the upper end of the key stem forward and the notch into engagement with the cover plate. Rearward pressure at the top of the key by the operator moves the notch 255 out of engagement with the cover and thus enables the spring 136 to restore the key to its raised position.

40 The right end of lever 133 (Figure 1) is bifurcated and engages a pin 139 laterally projecting from the free end of a pitman 141. The

45 75

rear end of the pitman 141 is pivotally supported by an eccentric 142 mounted for rotation with the gear 103 in the actuator drive train, so that upon each rotation of the gear 103 the pitman 141 is reciprocated. The free forward end of the pitman 141 is also provided with an upwardly extending projection 143, which normally stands in the disabled position shown. When the add key 250 is depressed to the position 250a shown by broken lines the lever 133 is rocked counter-clockwise raising its bifurcated end and the forward end of the pitman is moved upwardly to a position in which the projection 143 lies in front of a gate 144 pivoted to the frame of the machine.

Each of the key latching slides 13 described hereinbefore is provided with an upturned ear 146 at its rear end and the arrangement is such that gate 144 is positioned in front of these ears. Hence when the actuator drive train including gear 103 is driven by the main clutch 36 and pitman 141 is reciprocated, its projection 143, when elevated by depression of the add key, engages the gate 144 and rocks it backward thus sliding all the locking slides 13 rearwardly to their key releasing positions from where they may return to normal position under the influence of their restore springs 16 as further rotation of gear 103 moves pitman 141 with its projection 143 into its forward position.

One cycle stop mechanism

In machines provided with automatic multiplication mechanism by which the number of rotations of the accumulator actuator may be limited to any desired number between 1 and 9, depending upon the value of what key may have been depressed in a series of nine multiplier keys, depression of the add key may be arranged to enable the plus and minus bars to establish such a setting of the automatic multiplication mechanism as corresponds to that of the unit key of the multiplier keys, so that with the add key in depressed condition, depression of either the plus or minus bar will result in only one cycle of operation of the machine regardless of the duration of time during which these bars are held depressed. At the same time the add key is arranged to disable, upon depression, the automatic carriage shift that is usually provided in automatic multiplication mechanism so as to prevent undesirable operation of said shift during the performance of multiple additions, the details of such mechanism being described in my above mentioned Patent 2,256,799.

Add key release mechanism

As stated in the introduction to this specification division is performed on the machine of the type disclosed herein, and to which the present invention is applicable, by repeatedly subtracting the divisor set up on the keyboard from the dividend or current remainder standing in the accumulator register. Therefore, if the add key is in its depressed position such as might be the condition following an addition or subtraction calculation it is necessary to release the add key before the division calculation may be started.

To avoid the necessity of manually releasing the add key and moreover to avoid the possibility of the operator forgetting to do so, thereby losing the divisor by automatic release of the keyboard during the first division cycle I have provided a novel automatic add key release mechanism which is applicable to calculating machines whether they are of the type in which division is per-

formed under manipulation of the plus and minus bars or by hand crank, and whether they possess a division initiating key or not.

In accordance with my invention I employ a substantially horizontally positioned bar 147 pivotally supported by two links 148 and 149 which, in turn, are pivoted in the machine frame. The forward end of the bar 147 is provided with a cam face 152 having an oblique and a substantially vertical portion 152a and 152b, respectively, and which lies to the rear of, and slightly below, a pin 153 laterally projecting from the lower part of stem 131 of the add key 250.

When the add key 250 is depressed to the position indicated by broken lines, the pin 153 contacts and cams downward along the oblique portion 152a of the cam face 152 forcing the bar 147 rearwardly until the substantially vertical portion 152b of the cam face 152 lies immediately to the rear of the pin 153 in its depressed position.

Forward movement of the bar 147 will cause the vertical portion 152b of cam 152 to rock pin 153 and hence key 250 clockwise about the pivot 132, thereby releasing the notch 255 from engagement with the cover plate and permitting the spring 136 to return the add key 250 to its inoperative position.

As will be seen from Figure 1 of the drawings, rear link 149 is somewhat longer than the front link 148, and due to this and to the different angular positions of the links when the add key is in its raised condition, the rearward end of bar 147 will rock slightly downward when said bar is moved rearwardly as shown by the dotted line representation of bar 147 and of links 148 and 149 in Figure 1, which indicates the position of these parts when bar 147 has been pushed rearwardly by depression of the add key 250.

The necessary forward movement to release the add key is imparted to the bar 147 by a horizontal slide 156 (Figure 1) mounted for sliding movement on screws 157 which extend through slots in the slide 156. An extension 158 of slide 156 lies behind the downwardly extending rearward end 159 of the bar 147. The other end of the slide 156 is disposed in the path of a depending arm 161 of a bell crank 162 (Figure 3) pivoted at 163 to an intermediate frame of the machine. Normally a light spring 187 holds arm 161 of bell crank 162 against a stop 186 but when the bell crank 162 is rocked clockwise against the urgency of this spring 187 the said arm 161 engages the end of the slide 156, if it has previously been displaced rearwardly by depression of the add key, and forces the slide forwardly thereby releasing the add key in the manner heretofore described.

Add key release conditioning mechanism

In accordance with my invention I provide automatic mechanism to rock bell crank 162 into its add-key-releasing position and I so arrange matters that this mechanism must first be conditioned for effectiveness by operation of the counter clearance mechanism and, when thus conditioned, can be set into operation only by the accumulator actuator drive train operating in a negative or subtractive direction without any positive or additive operation having intervened. In accordance with my invention I provide additional means to restore the mechanism to its initial ineffective position after it has been operative. Also I so devise the add-key-release mechanism of my invention that when it has been conditioned for effectiveness, and the next

cycle of operation of the accumulator actuator drive train takes place in an additive direction, this will restore it to ineffective condition without releasing the add key.

The counter clearance shaft 116 (Figure 1) which is rotated through one complete revolution by operation of the clear clutch to clear the counter dials, carries a cam 117 which rotates with the shaft. This cam has a recess 117a adapted to receive a nose 113 of cam follower lever 110 mounted on a shaft 125. Upon rotation of the counter clearance shaft 116 the cam rocks cam follower lever 110 counter-clockwise, whereupon an ear 178 on a downwardly extending arm of said cam follower lever 110 engages an upwardly extending arm 177 (Figure 3) of a bell crank 173 and rocks the latter clockwise about its pivot 174 against the force of a spring 184. Spring 184 normally urges arm 177 counter-clockwise, as viewed in Figure 3, and arm 177 pressing against ear 178 urges the cam follower lever 110 (Figure 1) clockwise so that when cam 117 returns to its full cycle position at the end of a clear clutch cycle spring 184 presses nose 113 into the recess 117a of cam 117 and returns the parts to the positions shown.

An ear 171 is formed on the other arm 172 of the bell crank 173 and normally engages and blocks a nose 167a of an interponent 167 which is freely pivoted on a stud 166 carried on a rearwardly extending arm 164 of the bell crank 162 described hereinbefore. A torsion spring 168 urges the interponent 167 counter-clockwise about its pivot stud 166 so that when the interponent is released from the restraint of ear 171 it is rocked counter-clockwise by the spring and limited in that direction by a stop ear 169 formed on the rearward arm 164 of bell crank 162.

Operation of the add key release conditioning mechanism

The mechanism just described operates in the following manner to put the add key release mechanism into effective condition upon operation of the counter clearance device: When the counter is cleared, rotation of cam 117 moves cam follower lever 110 counter-clockwise which causes bell crank 173 to move clockwise withdrawing its ear 171 from underneath nose 167a of interponent 167. As a result thereof interponent 167 rocks toward the left, as viewed in Figure 3, under the urgency of spring 168 and moves its shoulder 183 underneath a stud 182 mounted on the gear 106 which, as described heretofore, is one of the gears in the drive train from the motor to the accumulator actuator. Upon operation of this drive train in a minus direction gear 106 is driven clockwise, as viewed in Figure 3, causing stud 182 to engage shoulder 183 and to drive the interponent 167 downwardly. This rocks bell crank 162 clockwise and releases the add key by actuation of the lever and linkage train described under the heading "Add key release mechanism."

The location of shoulder 183 on interponent 167 is so chosen that when interponent 167 is unlatched and in its forward position said shoulder 183 lies very closely below actuating stud 182 on gear 106 in its full cycle position. Consequently the add key release mechanism is put into operation at the very beginning of the subtractive cycle which initiates the add key release with the result that rocking projection 143 of pitman 141 is lowered into its idle motion position before rotation of shaft 104 and of eccentric 142 to draw it sufficiently to the rear of the machine to oper-

ate the release gate 144 of latching slides 13. Thus, in the very cycle which initiates release of the add key a value set up in the keyboard will no longer be released. For the same reason any one-cycle-stop mechanism that may be provided in the machine and which may have been in operation due to depression of the add key, is disabled at the very beginning of the subtractive cycle initiating release of the add key so that the machine will directly continue to operate uninterrupted over whatever number of cycles may be necessary to perform the particular division problem, undertaken.

Upon operation of the actuator in a plus direction, however, gear 106 moves upwardly or counter-clockwise so that stud 182 will not engage shoulder 183 and interponent 167 will not be actuated. The add key is therefore not released during an additive operation of the machine following operation of the counter clearance device.

Restoring means of the add key release conditioning mechanism

Means are also provided to restore the mechanism just described to its initial condition upon operation of the driving mechanism in either plus or minus direction the only difference being that during plus operation the mechanism is restored without releasing the add key whereas during minus operation the mechanism is restored after the add key has been released.

This restoring means comprises a cam 181 which is mounted for rotation with gear 106. An arm 197 of the interponent 167 (Figures 3 and 5) is formed around the outside and clear of gear 106 into the plane of cam 181. When the interponent 167, upon release of its nose 167a, is rocked counter-clockwise arm 197 comes to rest on the lower portion of cam 181. When the cam rotates with gear 106 it cams the interponent 167 clockwise with the result that the upper edge of the nose 167a cams ear 171 on the lower arm 172 of bell crank 173 upwardly until said nose passes beneath said ear whereupon spring 183 returns the bell crank 173 into the position shown in Figure 3 in which ear 171 engages nose 167a and blocks return of the interponent 167. The add key release mechanism is thus disabled throughout subsequent actuator cycles in either direction until again conditioned by operation of the counter clearing mechanism.

It should be noted that the mechanism of my invention is such that while it brings about the release of the add key on initiating calculation of division it does not interfere with the advantages offered by the add key mechanism in setting up the dividend and the divisor nor does it interfere with any of the other forms of calculations for which the machine may be employed. Thus, if the operator clears the counter and thereby conditions the add key release mechanism for operation before a dividend is entered into the accumulator register, the add key release mechanism will not operate during entry of the dividend due to the fact that the direction of operation of the driving mechanism is in a plus or additive direction when the operator introduces the dividend in the accumulator register; this plus operation will restore the add key release mechanism to ineffective condition and cause operation of the keyboard clearing mechanism for clearing the dividend out of the keyboard preparatory to setting the divisor therein. Also the add key will not be released upon operation of the driving mechanism in a subtractive di-

rection during subtraction problems. Operation of the counter clearance mechanism before a subtraction calculation is, of course, effective to condition the add key release mechanism for operation, but in subtraction calculations it is first necessary to enter the minuend into the accumulator register by a plus operation of the machine which disables the add key release mechanism in the same manner as the setting of a dividend in the accumulator as explained above. Consequently the following minus or subtract operation of the machine for subtracting the subtrahend from the minuend is ineffective to release the add key and is effective to automatically clear the keyboard in the usual way, the difference as against calculations of division being that whereas in calculations of division the result appears in the counter register, in calculations of subtraction the result appears in the accumulator register for which reason it is not necessary to clear the counter register after introducing the minuend into the accumulator register and before commencing operation of the machine in a minus direction which would condition the add key release mechanism for operation and cause release of the add key.

It will be understood that my invention is of particular advantage and applicability to the less expensive types of machine which have no division key or lever and in which the repeated subtractive operations necessary to perform division are effected by holding the minus key depressed for a selected period of time. My invention is equally applicable, however, to hand or motor driven machines having a special division key or lever such as division lever 600 (Fig. 6) which is manually set to initiate division operation; on the machine described in detail in the Avery and Lerch Patent No. 2,014,013 of which the aforementioned Patent No. 2,256,799 is a division. In such machines my invention provides automatic release of the add key on initiating calculations of division without burdening the operation of the division key or lever with additional trains of links and levers.

I claim:

1. In a calculating machine having a keyboard comprising settable numeral keys, means for locking said keys in set position, an accumulator register, a rotary actuator therefor, driving mechanism for rotating said actuator in either of two opposite directions, a counter register and clearing mechanism therefor; the combination of, means operable by said driving mechanism to release the keys from the locking means, said releasing means being adapted to be selectively enabled or disabled, with means operable to disable

said key releasing means, a train between said driving mechanism and said disabling means including an element normally in operating position to be actuated by said driving mechanism upon operation of the latter in one direction only to cause the train to operate said disabling means, a latch having a latching position in which it holds said element out of operating position and an unlatching position in which it enables the element to move to said operating position, and means driven by the counter clearing mechanism upon operation thereof to move the latch to said unlatching position.

2. In a calculating machine having a keyboard comprising settable numeral keys, means for locking said keys in set position, an accumulator register, a rotary actuator therefor, reversible driving mechanism operable in either of two opposite directions to rotate said actuator in either a plus or minus direction, a counter register and clearing mechanism therefor; the combination of, means operable by the driving mechanism to release the keys from the locking means, said releasing means being adapted to be selectively enabled or disabled, with means operable to disable said key releasing means, a train between said driving mechanism and said disabling means including an element normally in operating position to be actuated by said driving mechanism upon operation of the latter in the direction thereof which rotates the actuators in a minus direction only to cause the train to operate said disabling means, a driving member comprising a part of the driving mechanism and effective upon operation of the latter in either of its two opposite directions to move the element out of operating position, a latch having a latching position in which it holds said element out of operating position when moved thereto by said driving member and an unlatching position in which it enables the element to move to operating position, and means driven by the counter clearing mechanism upon operation thereof to move the latch to said unlatching position.

HAROLD T. AVERY.
